UNITED STATES PATENT OFFICE.

DAVID GEESNER, OF WORCESTER, MASSACHUSETTS.

CARD-CLOTHING FOR NAPPING-MACHINES.

SPECIFICATION forming part of Letters Patent No. 761,470, dated May 31, 1904.

Application filed October 11, 1902. Serial No. 126,876. (No model.)

To all whom it may concern:

Be it known that I, DAVID GEESNER, a citizen of the United States, and a resident of Worcester, county of Worcester, and State 5 of Massachusetts, have invented a new and useful Improvement in Card-Clothing for Napping-Machines, of which the following is a specification.

In my Patent No. 561,220 I have shown in 10 Figure 4 a napping-roll in which the card-clothing is spirally wound on opposite sides of the central transverse plane. In practice the application of the card-clothing in this manner has been attended with difficulty in consequence of the tendency of any uncovered space extending circumferentially to produce wrinkles in the cloth treated by the napping-roll. The card-clothing for napping-rollers is manufactured in narrow strips, generally from 15 three-fourths of an inch to seven-eighths of an inch in width, and the problem of winding such narrow strips so as to produce an opposite spiral on each half of the roll with the ends properly secured and without the objectionable circumferential vacant space above referred to is one that has not, I believe, been solved until my present invention.

In the accompanying drawings, Figs. 1, 2, and 3 represent in detail a form of fastening 20 or buckle that I prefer to use in carrying out my invention. Fig. 4 represents in plan and edge view an inserted piece or tongue employed in carrying out my invention. Fig. 5 is a detail showing a buckle part attached to 25 said tongue. Fig. 6 is a central portion of a napping-roll containing my invention.

1 is the napping-roll.

2 and 3 are the usual strips of card-clothing by which the opposite ends of the same are 30 covered.

4 is a strip of the outline *a b c d e f g h* shown in Fig. 4.

5 is a screw by which the smaller end of said tongue is secured to the roll.

6 and 7 are buckles or equivalent connecting parts by which the card-clothing strips 2 and 3 are respectively secured to the ears at the larger end of the tongue. These buckles may each consist of a plate *i*, containing the hook *j*, 45 and a plate *k*, containing the slot *l*, with which

said hook engages. The plates are respectively provided with suitable openings for the reception of the rivets *m*, by which they are secured to the card-clothing material.

A piece of card-clothing having been prepared in the form shown in Fig. 4 of sufficient width from *a* to *h* to provide sufficient body at that point to give a secure hold for the screw 5, is secured at that end by such screw to the roll and is wound around the roll until the ears 60 *b c* and *f g* straddle the end *a h*, as shown in Fig. 6. The said ears have already been provided with buckle members corresponding to buckle members riveted to the ends of two card-clothing strips 2 and 3. Thereupon the 65 said two card-clothing strips are secured by said buckles to said ears, respectively, and the napping-roll is turned, while the two strips are held in such position as to be wound in opposite spirals toward the opposite ends 70 of the roll, being secured, respectively, to the opposite ends of the roll in any suitable manner.

Although I do not wish to limit myself to the form of inserted strip or tongue shown in 75 Fig. 4, nevertheless said form possesses very decided advantages. It effectually fills up the vacant circumferential space left between the strips 2 and 3 by reason of its tapering or V-shaped form. No part of it is reduced to such 80 a narrowness as to break loose. It contains no projecting corners excepting such as are held down substantially by the buckles and the screw.

The wires *n* of the tongue 4 are laid, as indicated by dotted lines in Fig. 6, in circumferential lines, and their points are directed circumferentially, as indicated in the lower portion of Fig. 4. The wires *o* and *p* of the strips 2 and 3 are in lines parallel with the 90 edges of those strips, and their points are directed in planes parallel with such edges, so that when such strips are applied to the roll the points of their wires are directed in spiral lines diverging toward the opposite ends of 95 the roll. The position of the wires is thus adapted for causing the cloth to keep its width in passing through the machine and for removing or preventing lengthwise wrinkles. No attempt has been made in the drawings 100

to show this divergence in spiral lines of the points of the wires of the strips 2 and 3. The slight space occupied by the screw 5 and the buckles 6 and 7, although not occupied by 5 wires, extends principally longitudinally of the roll, and therefore has been found in practice to have no substantial tendency toward producing wrinkles.

Having thus described my invention, I claim 10 as new and desire to secure by Letters Patent—

1. As an article of manufacture, a tapered tongue of card-clothing adapted to be secured at its smaller end to a napping-roller and at its larger end to the ends of two card-clothing 15 strips.

2. As an article of manufacture, a card-clothing tongue, the side edges of which are at angles with the lines of wires thereon.

3. As an article of manufacture, a card-clothing 20 tongue, the side edges of which are at angles to the lines in which the points of its wires trend.

4. As an article of manufacture, a tapered card-clothing tongue, the field of its larger end

presenting two widths for the attachment of 25 card-clothing strips and an intermediate width corresponding with the smaller end of said tongue.

5. In combination, with the roller, two strips of card-clothing wound in opposite spirals and 30 an intermediate card-clothing tongue.

6. In combination, with the roller, two strips of card-clothing wound in opposite spirals, an intermediate card-clothing tongue and means of attachment between said strips and said 35 tongue.

7. In combination, with the roller, a tongue of card-clothing in which the lines of wire run circumferentially and two sections of card-clothing flanking the same in which the wires 40 run in opposite spirals.

In testimony whereof I have signed my name in the presence of two subscribing witnesses.

DAVID GEESNER.
